UNITED STATES PATENT OFFICE.

ROBERT HEAD, OF NEW YORK, N. Y., ASSIGNOR TO ROBERT L. WATKINS, OF NEW YORK, N. Y.

RHEOSTAT.

944,785.

Specification of Letters Patent. Patented Dec. 28, 1909.

Application filed October 27, 1908. Serial No. 459,719.

To all whom it may concern:

Be it known that I, ROBERT HEAD, a citizen of the United States, residing at New York city, in the county of New York and State of New York, have invented a new and useful Improvement in Rheostats, of which the following is a specification.

In stereopticons, photomicrographic cameras, motion picture machines and other devices employing electricity as a lighting medium, it is frequently found necessary to introduce within a circuit a rheostat or other resistance, which is usually bulky in construction and of considerable weight, therefore being exceedingly awkward to handle in transportation. It is also a fact that rheostats, as commonly constructed, retain the heat for quite a long time after the electric current has been cut off which in many instances is found to be an objectionable feature. It is with the view of eliminating these objectionable features and providing certain other improvements which will be found desirable in a rheostat used for the purposes above mentioned.

My invention therefore relates to improvements in rheostats, of a portable nature, and the objects of my improvements are: first, to provide a rheostat that will be light in weight and compact in form; second, to construct a rheostat that will remain comparatively cool while an electric current passes through it; and third, to present the greatest possible area of radiation, thus facilitating the rapid cooling of the rheostat after the current has been cut off. I attain these objects by the construction of a rheostat as illustrated in the accompanying drawings, in which—

Figure 1 is a perspective view of my improved rheostat in its preferred form, when in use; Fig. 2 is a view in elevation of the middle section, or frame of same; Fig. 3 is a sectional view showing the contacts and the hinge arrangement of the several sections, and is taken approximately on line 3—3 of Fig. 2. Fig. 4 is a view similar to Fig. 3, in which two of the sections are shown in their closed position, which throw them out of the circuit; Fig. 5 is an enlarged detail view of some of the contacts. In Figs. 6 and 7, I have shown a modification of the contact and hinge arrangement which may be found desirable under certain conditions.

Similar reference characters refer to like parts throughout the several views.

In the drawings illustrating one of the forms which my invention may take, 1, 2, 3, 4 and 5 designate the sections of which the rheostat is composed; the several sections are similar to the extent that they each consist of a metallic frame 6, in which four strips of mica or other suitable material 7, are secured. Upon each pair of the mica strips 7, is wound a resistance wire 8 of exceedingly small gage, the ends of which are electrically connected with the contact plates 9 and 9¹ which are suitably insulated from the frames 6.

In my rheostat, each section or member comprises a skeleton frame, a core composed of a plurality of pieces of insulating material, preferably mica, and a resistance wound on each piece of the core. The core pieces are positioned in the frame so that the side faces of the pieces are in the plane of, or parallel to, the corresponding side faces of the frame, said core pieces being arranged edge to edge, and practically in contact with each other. The resistance coiled on the core pieces are thus positioned in the plane of the frame, the looped parts of each resistance fitting over the edges of the core pieces on which it is wound and contacting with the edge of the next core piece, the convolutions of one coil alternating with the convolutions of the next coils, as shown in Figs. 1, 2 and 6. Said construction and arrangement of parts are advantageous for a number of reasons; first, the resistance windings are fully exposed on the respective sides of the frame to the circulation of air between and around the members composing the rheostat; second, a very compact and economical construction is secured, and, third, the number of resistance windings made possible by the number of core pieces secures an enlarged radiating area in each member of the rheostat.

Rigidly secured to the middle section 3, are angle plates 10, 10¹ provided with bearings 11 in which the trunnions of the sections 1, 2, 4 and 5 are journaled. To the underside of the plate 10¹ is hinged a member 12 having wings 12¹ projecting at right angles to the face thereof. The member 12 serves as a supporting leg, as shown in Fig. 1 when the rheostat is in use, and as a clasp to hold the sections together, when not in

use. The sections 1 and 5 are also provided with supports 18, adapted to be folded back against the frames 6, as indicated by dotted lines in Fig. 1.

5 The contact plate 9¹ of section 5 is provided with a downward projecting tongue or pendant 9² forming one of the terminals of the rheostat to which may be attached one of the wires 14, of an electric circuit. The 10 contact plate 9, of section 1 is also provided with a pendant similar to 9², to which may be attached the wire 15, Fig. 3, to complete the electric circuit.

15 As shown in the drawings, the wires 14 and 15 terminate in slotted plugs 14¹ and 15¹ and connection is established with the rheostat by forcing the pendants 9² of the contact plates 9 and 9¹, of the sections 1 and 5 respectively, into the slots of the plugs 14¹ 20 and 15¹. It is obvious however that many other methods of connecting the wires 14 and 15 to the rheostat may be employed within the scope of my invention.

25 In Fig. 5, which is substantially an enlarged view of Fig. 4, with two of the sections eliminated, I have shown in diagrammatic form the electric circuit and the manner in which the resistance of the middle section is cut out.

30 If the full resistance of the rheostat is desired, all the sections are opened, as shown in Figs. 1 and 3, in which position the electric current will be forced to traverse the resistance wires of all the sections. The 35 current may enter the rheostat through either of the terminals, but for the purpose of illustration we will assume it enters through the contact plate 9 of section 1 and passes along the resistance wire 8 thereof to the contact plate 9¹ of section 1, thence to contact plate 9 of section 2, along its resistance wire 8 to the contact plate 9¹ thereof and so on throughout the several sections of the rheostat leaving same by the contact 40 plate 9¹ of the last section 5. If however it is desirable to cut out the resistance of one or more of the sections, they may be returned to their closed position, as shown in Figs. 4 and 5.

45 In Fig. 4, the resistance of sections 2 and 3 is shown as cut out of the circuit, but for the purpose of better illustrating the method thereof, reference may be made to Fig. 5 wherein the resistance of the middle section 50 is in like manner cut out of the circuit.

55 It will be seen by referring to Fig. 5 that the current will enter the rheostat by the contact plate 9 of the first section and pass through the resistance 8 thereof, to the contact plate 9¹ of same, as previously stated; but in the present instance the current is 60 shunted to the contact plate 9¹ of the next section, via the rivet 6 and contact 17, thus avoiding the resistance of that particular section. The contact plate 9¹ of the section

just referred to and the plate 9 of the next section 5, being in contact with each other, the electric current will continue along the resistance 8 of section 5 and to the terminal thereof. It is evident therefore that the 70 different degrees of resistance offered by a rheostat as described, will be proportionate to the number of sections contained in the rheostat; it is also evident that at least one of the sections will always be included in the 75 circuit.

75 For purposes requiring a uniform resistance, I prefer to construct the rheostat as shown in Figs. 6 and 7 wherein the 6 frames of each of the sections 1, 2, 3, 4 and 5 are provided, respectively, with two insulated members 20 and 20¹; 21 and 21¹; 22 and 22¹; 23 and 23¹; 24 and 24¹ which in addition to forming terminals for the resistance wires of the several sections, also serve as hinge or swivel 80 joint, connecting the sections both mechanically and electrically to the post 25. The post 25 is made in two parts insulated from each other at 26. In the end of the upper part of the post 26, and in the side of the 85 lower part, I provide sockets 27 and 28 to receive the plugs 14¹ and 15¹, which form the terminals of the wires 14 and 15. In a rheostat of the above description, the electric current passes through the resistance wires 8 of all the sections at the same time, entering via the terminals 20, 21, 22, 23 and 24 from the upper part of the post 25, and leaving the several sections via the terminals 20¹, 21¹, 22¹, 23¹, and 24¹ to the lower section of the 90 post 25, or vice versa.

95 As a convenient means of elevating the rheostat slightly above the surface upon which it may be resting, I extend the front stile of the frames 6 of sections 1 and 5 slightly beyond the lower edge of the frames, and in like manner the lower part of the post 25 is extended, thus providing three legs or supports, 6¹ and 25¹.

100 As shown in Fig. 6 insulating pads 29 and 30 are secured to the ends of the legs 6¹ and 25¹. In a rheostat of the construction shown in Figs. 6 and 7, the resistance will be constant regardless of the relative position of the several sections, therefore the only apparent object in hinging the sections together, is that of compactness, which is the chief object sought in the present invention, and may be attained by folding the sections 110 together, bookwise, when the rheostat is not 115 in use.

120 While I have shown but two of the forms, my invention may take, I do not care to be limited thereto, as it is obvious that several modifications may be made without departing from the spirit of my invention.

125 I am aware that rheostats of a more or less bulky form, which usually become a permanent fixture when introduced into an electric circuit are in general use, I am also aware 130

that rheostats of both constant and variable resistances are in use, but I am not aware that heretofore any such improvements have been made in rheostats, as are embodied in my present invention, nor for the purposes herein set forth.

Therefore what I claim as new and desire to secure by Letters Patent is:

1. In a rheostat, a plurality of frames, 10 suitable supporting strips carried within said frames, resistance coils mounted upon the supporting strips and means operated by the relative movement of said frames for controlling the flow of current through said 15 resistance coils.

2. In a rheostat, a plurality of frames carrying supporting strips, suitable resistance material mounted upon said supports, means for yieldingly connecting the frames, and 20 means operated by the movement of the frames relative to each other for electrically connecting the resistance material of the several frames in series.

3. In a rheostat, the combination of a plurality of supporting frames, a hinge member connecting the several frames, supporting members secured within said frames, resistance material mounted upon the supporting members, insulated contact plates forming 30 terminals for the several sections of resistance; the contact plates of the various frames adapted to be thrown in or out of electrical contact with the plates of the frames adjacent thereto, substantially as shown.

35 4. In a rheostat, the combination of a plurality of supporting frames, a hinge connecting the several frames, supporting members secured within said frames, resistance material mounted upon the supporting members, insulated contact plates forming terminals for the several sections of resistance; the contact plates of the various frames adapted to be thrown in or out of electrical contact with the plates of the frames adjacent thereto, and supporting members for elevating the rheostat, adapted to be folded laterally against the frames substantially as shown and set forth.

5. In a rheostat, a plurality of sections 50 consisting of a suitable resistance material mounted upon supporting strips, said strips secured within a frame, a pillar or support consisting of two insulating sections, means for yieldingly connecting the sections to the pillar, and means for establishing electrical connection between the resistance material and the pillar substantially as shown and described.

6. In a rheostat, a member comprising an 60 open frame, a core composed of a plurality of pieces of insulating material, said core being positioned within the frame, and the pieces composing the core being assembled edge to edge with reference to each other, 65 and a plurality of resistances wound indi-

vidually on the core pieces, said resistances lying substantially in the planes of the respective faces of the frame.

7. In a rheostat, a member comprising an open frame, a plurality of core pieces positioned within said frame, said core pieces being assembled edge to edge with respect to each other and lying substantially in the planes of the respective faces of the frame, and a plurality of resistance windings coiled 75 individually on the core pieces.

8. In a rheostat, a member comprising an open frame, a plurality of mica cores positioned within said frame, said mica cores being assembled in edge to edge order, and 80 substantially in contact along their edges, and a plurality of resistances wound individually on said cores.

9. In a rheostat, a member comprising an open frame, a plurality of flat core pieces secured in said frame and positioned edge to edge with respect to each other, and resistance coils wound on said core pieces, the 85 windings of one resistance coil alternating with the convolutions of the next adjacent 90 coil.

10. In a rheostat, a member comprising a core composed of a sheet of mica divided to produce a series of lengths, said lengths being disposed in edgewise opposing relation, 95 and a resistance composed of a metallic winding supported by the mica sheet.

11. In a rheostat, a plurality of members 100 flexibly connected for adjustment relative to each other, whereby said members may be spaced for the circulation of air between them, each member having a resistance exposed to the air, and means operated by the adjustment of said members for regulating the flow of current through the resistances. 105

12. In a rheostat, a plurality of resistance members flexibly connected for adjustment into compact relationship and adapted to be separated for the circulation of air between and around said members, and means dependent upon the movement of said members for controlling the flow of current into the resistances thereof. 110

13. In a rheostat, a plurality of resistance carrying members adjustable into compact relationship and adapted to be relatively separated, and means dependent upon the positions of the members for controlling the flow of current through the resistances. 115

14. In a rheostat, a plurality of resistance carrying members adjustable into compact relationship and into spaced order, and means controllable by the adjustment of said members for cutting them into and out of an electric circuit. 120

15. In a rheostat, a plurality of adjustable resistance carrying members, and means controllable by the adjustment of said members for cutting them into and out of an electric circuit. 130

- 4
16. In a rheostat, a plurality of movable carrying members each having an exposed resistance, and means controllable by the movement of said members for cutting the resistances into or out of an electric circuit.
17. In a rheostat, a plurality of movable resistance members, means for supporting the same, and means controllable by the movement of said members for including them into an electric circuit.
18. In a rheostat, a plurality of movable resistance members each adapted to be exposed for the free circulation of air in contact therewith, and means operated by the movement of said members for cutting the resistances into and out of an electric circuit.
19. In a rheostat, a plurality of resistance members movable with respect to each other,
- whereby said members may be separated laterally, and means operated by the movement of said members for cutting them into or out of an electric circuit.
20. In a rheostat, a plurality of resistance members hingedly connected for lateral movement with respect to each other, and switch devices operated by the movement of said members for cutting them into or out of an electric circuit.

In witness whereof I have hereunto set my hand this 24th day of October 1908 in the presence of two subscribing witnesses.
